UNITED STATES PATENT OFFICE

CHARLES E. DILKES, OF NEWARK, NEW JERSEY

APPARATUS FOR EMBOSsing

Application filed January 16, 1929. Serial No. 332,774.

The present invention relates to apparatus for embossing cards or the like, and consists in the novel combinations and arrangements of elements hereinafter described and particularly set forth in the accompanying claims.

The purpose of the invention is to provide a machine which will operate to produce "embossed" cards, letter-heads, or the like in large quantities in an easy and convenient manner; one not requiring any special skill on the part of the operator, and wherein the initial cost of the apparatus and its expense in use will be substantially small with respect to like expense of present day apparatus for producing work of this character.

A further purpose is to provide an embossing machine which is portable to the end that it may be conveniently carried by a single person, stowed in small space, and otherwise readily adaptable to the exacting requirements of office equipment under modern business methods. And in short, it is the object of the present invention to offer in a single and compact machine all equipment necessary for producing embossed-like printed work to meet the ordinary requirements of any business establishment.

The invention is shown by way of illustration in the accompanying drawings, wherein:

Figure 1 is a perspective view of the machine complete.

Figure 2 a top plan view thereof, and;

Figure 3 a longitudinal sectional view of the same.

Referring to the construction in further detail, the apparatus consists of a suitable frame-work comprising similar side portions 3 of a height adapted for convenient handling when the entire apparatus is mounted on its foundation, e. g. table or the like, as shown.

The heating elements of the apparatus comprise a primary heating unit or rheostat 4 and a secondary heating unit or heat retaining substance 5 in the form of a stone or slab, that fits within and substantially covers the upper opening in the frame. A pair of lugs 6 on each frame member supports the slab 5 in the manner shown in Figure 3, and the upper surface of the slab provides

the table or work support for the conveyer means which carries the cards across the space between the heating units as will be understood.

A bracket-arm 7 is adjustably mounted on one of the frame sides 3, as by the wing-nut 8 to the end that the position of the rheostat 4 with respect to the stone or slab 5 may be positioned at will. This adjustable and removable feature for the rheostat and its associated parts also serves for facility in taking apart the units of the apparatus for the purpose of permanent storage, transportation, or the like.

A hood-like structure 9 preferably of sheet metal, and rectangular in design completely encloses the rheostat 4 and the lower edge of said hood lies closely adjacent the secondary heating element 5 thereby providing a substantially closed heat retaining area through which constantly pass the pre-treated cards to be "embossed."

The card conveyer consists of a plurality of endless belts or chains 10 that are mounted to travel across and in contacting relation with the upper surface of the stone 5 (see Figure 3) and at either end thereof is located an idle roller or bar 11 over which the conveyers 10 pass. A driven shaft 12 having a pulley or pinion 13 for each of the conveyer chains 10 is journaled in the frame members 3. Said shaft 12 carries a pulley 14 driven by the belt 15, said belt 15 being in turn driven by a smaller pulley 16 on counter-pulley 17; and said counter-pulley 17 has driving connection 18 with the pulley 19 on the armature shaft of the motor 20.

The motor 20 is equipped with an ordinary wire and plug connection, 21 and 22, for the usual electric socket; and the fields of the motor have conductor wires 23 connecting with the rheostat through a suitable supporting arm 24. An ordinary switch 25 is provided for the motor and a similar switch 26 for the rheostat.

It will be understood, of course, that the already printed cards having thereon the required "embossing" preparation are placed on the receiving ends of the conveyers thence carried through the heating or baking cham-

ber where the embossing effect is produced, and at the discharging end of the conveyers the "embossed" cards, letter-heads, or the like may be deposited on any suitable support, e. g. 5 inclined tray or shelf. And it will be further understood that the conveyers may be operated by manual power in the event electrical service is not available. In such case any suitable heater other than a rheostat 10 would necessarily need to be employed.

It will be evident that many changes in construction and arrangement of parts will be possible within the scope of the claims and the right of making such changes is reserved.

15 What is claimed as new is:

1. An apparatus for producing imitation embossing on cards and the like, comprising a supporting frame, a heating element and a heat retaining stone mounted thereon in 20 closely spaced relation, and a plurality of endless conveyers adapted to rest upon and pass over said stone for the purpose set forth.

2. An apparatus for producing imitation embossing on cards and the like, comprising 25 a supporting frame, a primary and a secondary heating element mounted thereon in closely spaced relation, and a plurality of endless conveyers adapted to travel over and in supporting contact with said secondary 30 heating element for the purpose set forth.

3. An apparatus for producing imitation embossing on cards and the like, comprising a supporting frame having an opening therein, a heating element located immediately 35 above said opening, a heat retaining stone mounted within said opening and lying flush with the upper frame surface, and a plurality of endless conveyers adapted to travel over and in supporting contact with said heat retaining stone, for the purpose set forth.

4. An apparatus for producing imitation embossing on cards and the like, comprising a frame, a primary heating element mounted 45 on the frame, a heat retaining stone mounted on the frame immediately beneath said primary heating element and providing a supporting surface, and an endless conveyer adapted to travel over and in supporting contact with said heat retaining stone, for 50 the purpose set forth.

In witness whereof, I have hereunto set my hand at Washington, District of Columbia, this seventh day of January, A. D. nineteen hundred and twenty-nine.

55 CHARLES E. DILKES.
